2,088,171

BOX

William Kaufman, Newark, N. J., assignor to Jiffie
Container Box Company, Newark, N. J., a cor-
poration of New Jersey

Application August 15, 1935, Serial No. 36,248

3 Claims. (Cl. 229—44)

This invention relates to boxes, containers and the like and refers more particularly to a cardboard box which may be made of a single blank.

An object of the present invention is the provision of a box which is preferably made of a single piece of material, such as a cardboard blank, and which is provided with at least two lids or covers which are conveniently disposed in relation to the main body of the container.

Another object is the provision of a container, the contents and/or the interior of which may be conveniently inspected and which is provided for that purpose, in addition to the usual top cover, with a front lid which may be opened or closed independently of the top cover.

The above and other objects of the invention may be realized through the provision of a container or box comprising a top cover which can be raised or lowered in relation to the main body of the container and an edge of which is in abutment with an edge of a movable front wall while the container is closed. The movable front wall is connected to the bottom of the container and may be opened or closed independently of said cover.

The invention will appear more clearly from the following detailed description when taken in connection with the accompanying drawings showing by way of example a preferred embodiment of the inventive idea.

In the drawings:

Figure 1 is a perspective view of the closed box.

Figure 2 is a perspective view of the box with its side wall open.

Figure 3 is a perspective view of the box with its cover open.

Fig. 4 is a perspective view showing the box with both its front wall and its cover open.

Fig. 5 illustrates the blank which when folded forms the box shown on Figures 1 to 4 of the drawings.

Fig. 6 is a section along the line 6—6 of Figure 3 on a larger scale.

The box illustrated in the drawings comprises a bottom 10, a side wall 11, a rear wall 12 and a side wall 13.

As is apparent from Figure 5 of the drawings, the walls 11, 12 and 13 are bent at right angles to bottom 10 while the box is being manufactured.

The edge 14 of the rear wall 11 is glued or connected in some other suitable manner to the edge 15 of the rear wall 12. The edge 16 of the rear

wall 12 is connected in the same manner to the edge 17 of the side wall 13.

The cover 18 of the box forms a continuation of the side wall 11. The cover 18 may be connected by hinges with the wall 11, or if the box is made of a single cardboard blank, the cover 18 may be folded along the line 20 in relation to the side wall 11.

A strip 19 consisting of a paper or textile material may be pasted over the edge 20 to prevent tearing. Similar strengthening strips 21 may be pasted over the abutting edges 16 and 17 as well as the abutting edges 14 and 15.

The cover 18 comprises two downturned flanges 22 and 23 which extend at right angles to the surface of the cover 18 and which comprise the edges 25 and 24, respectively, (Fig. 5). These edges 24 and 25 are brought in contact with one another when the flanges 22 and 23 are bent at right angles to the cover 18, and are joined by gluing or the like.

As shown more clearly in Figures 1 and 2 of the drawings, the width of the flanges 22 and 23 is substantially equal to or only somewhat less than the height of the walls 12 and 13. When the box is closed, the flange 23 overlaps the wall 13 and covers the major portion of this wall. Similarly, the flange 22 covers the major portion of the rear wall 12.

In a box manufactured in accordance with the present invention, the front wall 26 is made movable in relation to the bottom 10 and the walls 11, 12, and 13. The front wall 26 may be connected by hinges to the bottom 10 or it may be made of the same blank as the bottom 10 and folded along the line 27, (Figure 5). A strengthening strip 28 consisting of paper or a fabric may be pasted over the edge 27, as shown in Figures 2 and 4.

While the upper edge 28 of the side wall 13 forms a right angle with the side edge 17 of this wall, the edge 29 of the wall 13 forms an obtuse angle with the edge 28. Similarly, the second side edge 30 of the side wall 11 forms preferably the same obtuse angle with the folding line 20. Due to this arrangement, the edges 30 and 29 form slanting lines when the box is completed.

The movable front wall 26 comprises two triangular side flanges 31 and 32 and a top flange 33. It will be apparent from Figure 5 of the drawings, that when the side flanges 31 and 32 and the top flange 33 are bent at right angles to the surface of the front wall 26, the edge 34 of the side flange 31 is brought adjacent to the

edge 35 of the top flange 33. Similarly the edge 36 of the side flange 32 is brought in contact with the edge 37 of the top flange 33.

5 The edges 34 and 35 are joined one to the other by gluing or the like. The edges 36 and 37 are joined one to the other in the same manner.

10 The angles formed between the edges 38 and 39 of the side flanges 31 and 32 on the one hand, and the folding lines 40 and 41 on the other hand, are complementary to the angles formed between the edges 29 and 30 on one hand and the folding lines 42 and 43 on the other hand. Due to this arrangement the edges 38 and 39 coincide exactly with the edges 30 and 29 when the front 15 wall 26 is closed, as shown in Figures 1 and 3 of the drawings.

15 The top flange 33 of the movable front wall 26 forms a continuation of the cover 18. When the box is closed, the edge 44 of the top flange 33 20 coincides exactly with the edge 45 of the cover 18.

25 Resilient means are preferably used for maintaining the edges 44, 33 and 39 of the movable front wall 26 in contact with the edges 45, 30 and 29 of the box.

30 While a number of different means may be used to accomplish the same result, in the example illustrated, such means comprise a pair of rubber bands 46 and 47. The rubber band 46 is passed around the knob 48 carried by the side flange 32 of the movable wall 26 and the knob 49 carried by the side wall 13.

35 As shown in Figure 6, the knob 49 may be screwed upon a suitable nut 50 passing through an opening formed in the side wall 13.

40 The side wall 11 carries a similar knob 50. The rubber band 47 passes around the knob 50 and a knob 51 which is carried by the side flange 31 of the movable front wall 26.

45 The box illustrated in the drawings may be used for a number of different purposes. Due to the provision of a movable front wall 26, the contents of the box may be conveniently inspected and removed without opening the cover 18. This arrangement is particularly advantageous in the case of narrow and long boxes containing a number of objects placed side by side, such as papers, plates and the like.

50 An important feature of my improved construction resides in the arrangement or relation of the parts with respect to each other so that the elastic means 46, 47 has a dead-center position and operates when on one side thereof to hold the movable wall closed against the two adjacent walls 11 and 13, as shown in Figs. 1 and 3. Further, it will be seen that the elastic means 46, 47 is movable to the other side of the dead-center position upon movement of the movable wall 26

through an angle greater than ninety degrees from its closed position, as shown in Figs. 1 and 3, to its open position, as shown in Figs. 2 and 4, in which case the elastic means operates to hold the movable wall in its open position.

5 Many different changes may be made in the described construction without departing from the spirit of the present invention. For instance, the box may be made of several separate pieces and out of any suitable material.

10 What is claimed is:

15 1. A box and the like, comprising a bottom, three walls firmly connected with said bottom, a cover rotatably connected with one of said walls, said cover comprising two flanges adapted to overlap the other two of said walls when the box is closed, and a fourth wall rotatably connected with said bottom, said fourth wall comprising a top flange having an edge adapted to coincide with an edge of said cover when said box is closed. 20

25 2. A box and the like, comprising a bottom, three walls firmly connected with said bottom, a cover rotatably connected with one of said walls, said cover comprising two flanges adapted to overlap the other two of said walls when the box is closed, a fourth wall rotatably connected with said bottom, said fourth wall comprising a top flange having an edge adapted to coincide with an edge of said cover when said box is closed, and side flanges having edges adapted to coincide 30 with edges of two of the other walls when said box is closed; and resilient closing means connected with two of the walls and said side flanges and adapted to maintain said fourth wall in a closed position.

35 3. A box comprising a bottom and walls, one of said walls being connected to said bottom for pivotal movement with respect thereto from a closed position through an angle greater than ninety degrees to an open position, the respective 40 complementary edges of the movable wall and the two walls adjacent to the movable wall being cut on a bias, said movable wall being provided with a flange forming part of a cover for the box when said movable wall is in its closed position, elastic means having a dead-center position and operable when on one side thereof to hold the movable wall closed against said two adjacent walls, said elastic means being movable to the other side of said position upon pivotal movement 45 of the movable wall through said angle and operable thereat to hold the movable wall in its open position, and a cover for closing said box and having an edge which coincides with the adjacent edge of said movable wall when the cover is 50 in position to close the box.

55 WILLIAM KAUFMAN.
